Primary Examiner—Catherine Tuttle*(74) Attorney, Agent, or Firm*—Panitch Schwarze Belisario & Nadel LLP(57) **CLAIM**

The ornamental design for a remote control unit, as shown and described.

DESCRIPTION

FIG. 1 is a perspective view of the front, right and upper sides of a remote control unit according to the design;

FIG. 2 is a perspective view of the rear, left and upper sides thereof;

FIG. 3 is a front elevation view thereof;

FIG. 4 is a rear elevation view thereof;

FIG. 5 is an elevation view of the left side thereof, the right side being a mirror image; and,

FIG. 6 is a top plan view thereof.
